Inventor:

Arthur C. Braun,

BY *Samuel A. Cook*,
Attorney.

UNITED STATES PATENT OFFICE

168,781

BEAD OR SIMILAR ARTICLE

Arthur C. Braun, Summit, N. J.

Application August 15, 1952, Serial No. 21,051

Term of patent 3½ years

(Cl. D45—1)

To all whom it may concern:

Be it known that I, Arthur C. Braun, a citizen of the United States of America and a resident of Summit, county of Union and State of New Jersey, have invented a new, original, and ornamental Design for a Bead or Similar Article, of which the following is a specification, reference being had to the accompanying drawing, forming a part thereof.

Figure 1 is a front elevational view of a bead embodying the new design;

Figure 2 is a top plan view of the bead of Fig. 1.

I claim:

The ornamental design for a bead or similar article, as shown.

ARTHUR C. BRAUN.
